U.S. Cl. D6—164

FIG. 3

FIG. 1

FIG. 2

FIG. 1 is a front-perspective view of a storage compartment for use within signs showing my new design. FIG. 2 is a rear-perspective view of the storage compartment of the FIG. 1.

FIG. 3 is a front-perspective view with the door shown in the open position with a portion of a sign and the letter inserts shown in broken lines for illustrative purposes only.

The characteristic feature of my design resides in the specific appearance of the inner drawer units having parallel dividers, said units being enclosed by a door as best shown in FIGS. 1 and 3.

I claim:

The ornamental design for a storage compartment for use within signs, substantially as shown and described.
